UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

COKE QUENCHING AND LOADING DEVICE.

Application filed July 8, 1921. Serial No. 483,145.

(GRANTED UNDER THE PROVISIONS OF THE ACT OF MARCH 3, 1921, 41 STAT. L., 1313.)

To all whom it may concern:

Be it known that I, HEINRICH KOPPERS (assignor to The Koppers Development Corporation, a corporation of Pennsylvania), a citizen of Germany, residing in Essen-Ruhr, Germany, have invented a new and useful Improvement in Coke Quenching and Loading Devices (for which application for patent has been filed in Germany on or about March 18, 1920), of which the following is a specification.

A prior design (not claimed in my present application) relates to a coke quenching and loading device, by means of a quenching car with a slanting bottom and a stationary ramp adjoining the same and inclined at about the sliding angle of the coke, to which the coke can be transferred or conveyed without a free fall and where it spreads out in a comparatively thin layer, so that it can be quenched and discharge the vapors as may be required. The entire arrangement is based on the guiding principle of vouchsafing an economical quenching of the coke and as gentle a treatment or handling of it as possible during the transfer. According to another prior design (not claimed in my present application) the ramp constitutes the medium between the quenching car and the screening device, there being arranged in front of the ramp a movable screening device which has a bucket elevator extending thereunder for the purpose of receiving the coke as needed.

Instead of conveying the coke first from the stationary ramp to the height of the screening device, it is advisable in many cases to arrange the ramp itself at the proper height above the screening device and to lift the coke quenched in the quenching car to the level of the ramp. The idea of doing this by elevating the quenching car itself for the required distance, for instance by the use of inclined planes, meets with practical difficulties for the reason that the quenching car is extremely heavy. In order to be able to resist the action of the glowing coke, the entire quenching car must be built heavy and solid; thus, for instance, its lining of heavy cast plates is absolutely essential. The lifting of this dead weight, especially together with the entire charge of such a quenching

car, means a considerable expenditure of energy.

So as to be able to transport the coke to the high level ramp, while avoiding such conveying devices as are hereinabove mentioned, bucket elevators, conveying belts and the like, the coke quenched on the quenching car is first taken, according to the invention, to an intermediate receptacle provided with a slanting bottom, this receptacle being lifted to the height of the slanting stationary platform of the high ramp and the coke permitted to slide off from said intermediate receptacle to the latter. Since these intermediate receptacles do not come into contact with unquenched coke, they can be built lighter than the coke quenching cars themselves; furthermore it is possible to subdivide these intermediate receptacles into several smaller ones for receiving the charge from a coke quenching car, whereby the amount of lifting energy required is still further reduced.

Since for practical reasons the screening device to be arranged at the end of this stationary throw-off ramp comprises individual screens to be operated by themselves, for instance in the shape of roller grates which can be started or stopped by means of stowing rakes or the like, the possibility is at once afforded of loading both blast furnace buckets and standard railway cars. The subdivision of the screening devices in this connection is from the first carried out and dimensioned in such a way that the blast furnace buckets disposed in the customary manner in a certain number, for instance in sets of five on a common truck, can be loaded simultaneously and uniformly by operating all of the screening devices, while for loading railway cars the central screening devices, for instance, can be put out of commission in order to avoid a spilling of the coke in the space between the two railway cars.

In order to prevent, especially in connection with the charging of blast furnace buckets, a subsequent breaking up of the coke such as is easily brought about by a great height of fall, an auxiliary arrangement is provided here which consists of an auxiliary chute assigned to the discharge or outlet of

the screening devices and which is displaced against this discharge by the load. This brings about such a deflection of the coke and breaks the fall of the same in such a way 5 that both a proper or gentle handling of the coke and a uniform filling of the charging vessels are effected.

In order to make the invention more 10 clearly understood, without limiting its useful applications to that particular embodiment which has been chosen for the purposes of illustration and explanation, there is shown in the accompanying drawings a practical use of the same.

15 In said drawings—

Fig. 1 is an elevation, partly in section, of a coke quenching and loading device embodying the invention.

20 Fig. 2 is a plan view of the same.

Figs. 3, 4 and 5 show, on a larger scale, the auxiliary arrangement, in various positions, for charging the coke into blast furnace buckets.

25 Fig. 6 is a fragmentary perspective view showing a plurality of stowing rakes associated with the roller grate screens, and showing the subdividers.

Fig. 7 is a perspective view of the auxiliary chute.

30 The coke coming from the oven 10 and pressed on to the quenching cars 11 with slanting bottoms is taken to the quenching station and quenched there by irrigation. The car then goes in front of the frame 12

35 in which the receptacles 13 are arranged, which also possess a bottom inclined at the sliding angle of the coke and which can thus be loaded without injuring the coke. In order not to make the individual receptacles 13

40 unduly heavy in this connection two such are provided in each case for the length of the quenching car 11. A spur 14 which works after the fashion of an ice pick or breaker, sees to it in this connection that 45 the load of the quenching car 11 is uniformly distributed between the two receptacles 13. By means of the winches 15 the receptacles 13 are lifted far enough in the frame 12 to make their lower edge flush with

50 the upper edge of the slanting stationary platform 16, so that the coke can slide from said receptacles over on to this platform, where it spreads out to discharge the vapors or to be after-quenched. At the lower end 55 of the platform 16 the roller grates or screens 17, five in number as shown, are arranged, between which, also after the manner of ice breakers, subdividers 18 are provided. By means of the stowing rakes 19

60 the individual roller grates 17 can be closed off from the platform 16. Underneath the grates 17 the receptacles 20 are arranged for the reception of the finely screened coke and can be emptied, as required, onto a conveying belt 21 or the like.

According to the opening of the stowing rakes 19 and the operation of the roller grates 17 it is possible to discharge the coke at the desired places, so that, for instance, by operating all of the roller grates 17 it 70 is possible to charge the blast furnace buckets 23 likewise arranged in sets of five on a common truck 22. By means of the subdivision described, the feeding of the coke in the requisite quantity for each bucket is insured. The loading of standard railway cars can be effected by only utilizing perhaps two or three of the roller grates 75 17 or by disconnecting the central roller grate in connection with railway cars standing in series, in order to prevent a spilling of the coke between the railway cars.

Under the discharges 24 of the individual roller grates 17, are provided the auxiliary chutes 25 which are provided with elongated slots intermediate their sides and extending a short distance toward the top of the chute so that when the chute is lowered to the position shown in Figure 3 the hanger rods 26 will extend through said slot and allow the chute to enter into the buckets 23. These chutes 25 are so movably supported that they can assume consecutively the positions shown in Figs. 3 to 5, so that the coke describes a zig-zag route (with little fall), which not only prevents its being broken up but also insures at the same time a uniform filling of the buckets 23.

What is claimed is—

1. The combination of a coke quenching oven, a coke support having an inclined bottom for receiving coke from said oven, a vertically movable coke support having an inclined bottom for receiving coke from said first support according to the sliding angle of said coke, an elevated inclined coke holding and cooling ramp for receiving coke from said vertically movable support, and screening and loading means arranged to receive coke from said ramp. 100

2. The combination of a coke oven, a horizontally movable coke quenching support having an inclined bottom for receiving coke from said oven, an elevated coke cooling inclined ramp having screening and loading means, and a coke support having an inclined bottom and movable to a point below said quenching support to receive coke therefrom according to the sliding angle of said coke and movable to a point above said ramp to deliver coke thereto. 105

3. A coke-quenching support having an inclined bottom and means on said support for separating the load of coke as it slides therefrom, and a coke support movable to a point below said quenching support to receive its part of said load and movable to an elevated point to deliver the same. 115

4. The combination of an elevated, inclined ramp, means for supplying coke there-

- to, means for subdividing the coke as it passes from said ramp, and individually operable screening devices, each screening device being arranged to receive a subdivided part of said coke, whereby all of said screening devices can be operated to deliver coke into blast furnace buckets, or certain of said screening devices can be operated to deliver coke into railway cars without delivering the same at points between said cars. 40
- 5 5. A coke quenching and loading device comprising, in combination: an inclined stationary coke holding and cooling ramp; a plurality of coke screening members associated with said ramp at its lower end; a coke quenching car having an inclined bottom; a plurality of vertically movable receptacles, each having an inclined bottom, interposed between said coke quenching car and said ramp. 45
- 10 6. A coke quenching and loading device comprising, in combination: an inclined stationary coke holding and cooling ramp; a plurality of coke screening members associated with said ramp at its lower end; a coke quenching car having an inclined bottom; a plurality of vertically movable receptacles, each having an inclined bottom, interposed between said coke quenching car and said ramp. 50
- 15 7. A coke quenching and loading device comprising, in combination: an inclined stationary coke holding and cooling ramp; a plurality of coke screening members associated with said ramp at its lower end; a coke quenching car having an inclined bottom; a plurality of vertically movable receptacles, each having an inclined bottom, interposed between said coke quenching car and said ramp. 55
- 20 8. A coke quenching and loading device comprising, in combination: an inclined stationary coke holding and cooling ramp; a plurality of coke screening members associated with said ramp at its lower end; means individual to and associated with each of said screens for shutting off the supply of coke from the ramp to the screens. 60
- 25 9. A coke quenching and loading device comprising, in combination: a coke quenching car having an inclined bottom; an inclined coke holding and quenching ramp; a vertically movable receptacle having an inclined bottom interposed between said car and said ramp; screening means at the lower end of said ramp and associated therewith over which the coke passes on its way to a receptacle; an inclined chute on which the coke falls as it leaves the screening means, said chute being mounted to enter the receptacle and be withdrawn gradually therefrom while the receptacle is being filled in order that the coke may be supported while entering the receptacle. 65
- 30 10. The combination of a coke oven, a horizontally movable coke quenching car for receiving hot coke from said oven, an elevated inclined ramp and a coke support having an inclined bottom and movable to a point below said coke quenching car and movable to a point above said ramp to deliver coke thereto. 70
- 35 35 7. A coke quenching and loading device comprising, in combination: an inclined stationary coke holding and cooling ramp; a plurality of coke screening members associated with said ramp at its lower end; a

HEINRICH KOPPERS.
